UNITED STATES PATENT OFFICE.

ALPHONSE R. PERRIN, OF WESTBROOK, MAINE.

SLUB CATCHER.

Application filed April 15, 1926. Serial No. 102,190.

The invention relates to a slub catcher for winding machines.

The object of the present invention is to improve the construction of slub catchers more especially that shown and described in my copending application filed April 28, 1925, Serial No. 26,475, now Patent No. 1,585,315, and to provide an exceedingly sensitive slub catcher of simple, practical and inexpensive construction adapted to positively prevent slubs from passing to the spool on which the yarn is being wound.

With these and other objects in view, the invention consists in the construction and novel combination and arrangement of parts hereinafter fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:—

Figure 1 is a plan view of a slub catcher constructed in accordance with this invention.

Fig. 2 is a transverse sectional view on the line 2—2 of Fig. 1.

Fig. 3 is a side elevation partly in section the portion in section being taken substantially on the line 3—3 of Fig. 2.

Fig. 4 is a rear elevation of the slub catcher.

In the accompanying drawing in which is illustrated the preferred embodiment of the invention, the slub catcher comprises in its construction a supporting bracket 1 provided at its lower portion with a sectional clamp 2 for mounting it in position and having a front yarn guide 3 and a tension device 4. The supporting bracket is provided in rear of the tension device with a smooth face or jaw 5 over which the yarn passes. The jaw 5 which is fixed preferably consists of a horizontal laterally extending arm round in cross section and recessed at the front at 6 to receive the lower portion of a floating feeler finger 7 which is pivotally mounted on the upper portion of the bracket and which is constructed approximately the same as that shown and described in the aforesaid application.

The supporting bracket is provided with

a substantially vertical transversely disposed upwardly extending portion 8 having a substantially rectangular opening 9 in its lower portion and having its outer side or portion 10 located above and spaced slightly from the fixed horizontal jaw 5. The feeler finger is mounted on a pivot 11 located at the front of the transverse portion of the supporting bracket and arranged above the opening 9 and consisting of a projection extending forwardly and upwardly forming substantially a hook to receive an eye or opening 12 of the floating feeler finger. The floating feeler finger is approximately L-shaped, being provided at its upper portion with a weighted arm 13 which operates to swing the feeler finger towards the outer side 10 of the transverse portion of the bracket. The bracket is provided with a stop 14 consisting of a pin and located beneath the weighted arm for limiting the downward swing thereof and for maintaining the feeler finger when unthreaded in convenient position adjacent the said outer side 10 of the bracket to receive the yarn and enable the same to be readily threaded after a breaking thereof or after one batch of yarn has been exhausted. The feeler finger is provided at its lower portion with a slot 15 to receive the yarn and the slotted portion of the feeler finger terminates at the outer side of the slot above the portion at the inner side of the slot to enable the yarn to be readily introduced into the slot. The extended portion of the feeler finger at the inner side of the slot forms a guide for directing the yarn into the slot. The slot preferably terminates at its upper end in an eye or opening as shown. The feeler finger is detachably hung on the substantially hook-shaped pivot 11 and it is adapted to swing transversely of the bracket and also has a limited swinging movement longitudinally in the direction of the movement of the yarn and its lower yarn receiving portion in use slides or moves along a lower cutting edge 16 of a hinged upper plate or member 17 constituting a movable jaw and cooperating with the fixed jaw 5 to form a yarn gripper. The hinged jaw is mounted in the opening 10 of the bracket on a horizontal pivot 18 which extends across the opening 10 and which is mounted in suitably aligned perforations of the transverse portion of the

bracket. The horizontal pivot 18 is preferably movable to enable the hinged jaw to be readily placed in and removed from the supporting bracket. The hinged jaw of the gripping device is approximately U-shaped in vertical section and extends upwardly and rearwardly and then downwardly and forwardly, the lower side being extended beyond the upper side and projecting through the opening in the bracket and the said cutting edge 16. The particular shape of the hinged jaw throws the center of gravity above and in rear of the horizontal pivot 18 so that the tendency of the hinged jaw is to swing forwardly, the forward movement being limited by a stop 19 consisting of an integral lug projecting laterally at one side of the hinged jaw and engaging the outer side 10 of the transverse portion of the bracket at the rear face thereof. This maintains the cutting edge in a forward projecting position and also in spaced relation with the fixed jaw to provide a passage for the yarn.

25 The yarn passes through the slot of the feeler finger and through the yarn gripper, the feeler finger floating with the yarn and sliding on the cutting edge of the hinged jaw and when a slub reaches the feeler finger it turns to a vertical position to pass through the slot of the feeler finger and is then instantly caused to twist and turn to a horizontal position by the cutting edge of the hinged jaw of the gripping device. This will either break the slub or cause the slub to swing the hinged jaw into engagement with the fixed jaw and break the thread. As the feeler finger is in contact with the cutting edge of the hinged jaw and slides on the same in any transverse movement of the feeler finger the hinged jaw causes the instant twisting of a slub and produces a positive breaking of the same. The feeler finger is adapted to move backwardly with the hinged jaw of the gripping device in the closing movement thereof and there will be no opportunity by reason of any spacing of the feeler finger from the cutting edge of the movable jaw passing through the slub catcher without causing a breakage of the yarn. Slubs consist of soft untwisted portions of the yarn and will ordinarily pass through an opening of a size sufficient to permit the passage of the yarn but it has been found that the flattening of the slub to pass through the slot of the feeler finger and the instant twisting of the slub at right angles will positively produce a breaking of the slub or an operation of the yarn gripper and a consequent breaking of the yarn. The hook-shaped pivot of the feeler finger will enable feeler fingers to be readily removed from and placed on the supporting pivot so that a feeler finger having a slot of the required size may be readily placed in

position to suit the size of the yarn being wound.

What is claimed is:

1. A slub catcher comprising a supporting bracket having a fixed jaw, a movable jaw hinged to the supporting bracket above the fixed jaw and normally spaced slightly above the same to provide a passage for the yarn and adapted to swing downwardly into contact with the fixed jaw and a pivoted floating feeler finger having a yarn slot and slideable on the lower edge of the jaw whereby a slub will be twisted by the feeler finger and the movable jaw and either broken by such twisting or gripped and broken by the closing of the hinged jaw. 70

75 2. A slub catcher comprising a supporting bracket having a fixed horizontal jaw, a movable jaw hinged to the supporting bracket above the fixed jaw and having a horizontal cutting edge normally spaced slightly above the said fixed jaw and adapted to swing downwardly into contact with the fixed jaw, and a pivoted floating feeler finger having a substantially vertical yarn slot and slideable on the cutting edge of the jaw in its floating action whereby a slub passing through the slot of the feeler finger is twisted substantially at right angles by the cutting edge of the hinged jaw to break 80 the slub by the twisting thereof or by closing the jaw on the slub. 85

90 3. A slub catcher comprising a supporting bracket having a fixed horizontal jaw and provided above the same with an opening, a movable jaw hinged to the supporting bracket at the upper portion of the opening and extending forwardly through the opening from the back of the bracket and provided with a lower horizontal cutting edge 100 normally spaced slightly above the fixed jaw and a pivoted floating feeler finger provided with a substantially vertical yarn slot and slideable on the cutting edge of the hinged jaw whereby a slub passing through the slub catcher is given a half twist to break the slub either by such twisting of the same or by closing the hinged jaw on the slub. 105

110 4. A slub catcher comprising a supporting bracket having a fixed horizontal jaw, a movable jaw hinged to the bracket above the fixed jaw and provided with a lower horizontal cutting edge, said hinged jaw having its center gravity in rear of the vertical plane of the pivot for causing the cutting edge 115 to project forwardly through the bracket in slightly spaced relation with the fixed jaw and a pivoted floating feeler finger having a yarn slot slideable in its floating action on the cutting edge of the hinged jaw. 120

125 5. A slub catcher comprising a supporting bracket having a fixed horizontal jaw, a movable jaw hinged to the bracket above the fixed jaw and provided with a lower horizontal cutting edge, said hinged jaw having 130

- its center gravity in rear of the vertical plane of the pivot for causing the cutting edge to project forwardly through the bracket in slightly spaced relation with the fixed jaw 5 and a pivoted floating feeler finger having a yarn slot 30 slidable in its floating action on the cutting edge of the hinged jaw, and a stop carried by the hinged jaw and arranged to engage the bracket for limiting the forward 10 movement of the said bracket.
6. A slub catcher comprising a supporting bracket having a fixed horizontal jaw and provided above the same with an opening, a movable jaw hinged to the bracket at the 15 upper portion of the said opening and having a lower horizontal cutting edge projecting through the opening, said hinged jaw being extended upwardly and rearwardly from the bracket and then downwardly and forwardly to the lower portion of the opening whereby the center of gravity is in rear of the pivot of the jaw and the latter caused to swing forwardly, a stop carried by the hinged jaw and arranged to engage the bracket to limit the forward movement of 20 the said jaw to maintain the cutting edge normally spaced slightly above the fixed jaw and a floating feeler finger pivoted to the bracket above the said opening and pro- 25 vided at its lower portion with a yarn slot 30 and slidable on the cutting edge of the hinged jaw in its floating action.
7. A slub catcher comprising a supporting bracket having a transverse portion provided with an opening, said bracket having a fixed 35 horizontal jaw at the bottom of the opening, a movable jaw hinged to the bracket at the upper portion of the opening and having a lower horizontal cutting edge normally spaced slightly above the fixed jaw and ar- 40 ranged to swing downwardly into contact with the same, a pivot projecting from the bracket above the said opening and extending upwardly in substantially hook formation, a floating feeler finger detachably hung from the said pivot and having a lower slot- 45 ed portion slidable on the cutting edge of the hinged jaw, said feeler finger being pro- 50 vided at its inner side with a projecting arm forming a weight for urging the feeler finger towards the outer side of the bracket and a stop projecting from the bracket and ar- 55 ranged to receive the weighted arm of the feeler finger.

In testimony whereof, I have hereunto set my hand.

ALPHONSE R. PERRIN.
